UNITED STATES PATENT OFFICE.

WILLIAM KLOCKE, OF WOODHAVEN, NEW YORK, ASSIGNOR TO E. W. BLISS COMPANY, OF BROOKLYN, NEW YORK, A CORPORATION OF WEST VIRGINIA.

DRAWING PRESS.

Application filed November 21, 1922. Serial No. 602,470.

To all whom it may concern:

Be it known that I, WILLIAM KLOCKE, a citizen of the United States of America, residing in Woodhaven, Queens County, city 5 and State of New York, have invented certain new and useful Improvements in a Drawing Press, of which the following is a specification.

This invention relates to presses of the 10 type having a yielding forming part or tool, and aims to provide improvements therein.

The invention provides a press wherein the reaction of the yielding forming part 15 is substantially constant or uniform throughout its movement.

The invention further provides a press in which the means for reacting on said yielding part makes use of fluid pressure, the 20 ambient air, the means being a so called vacuum means. The reacting means is furthermore preferably a self-contained means, acting to directly produce a vacuum, and obviating the use of pumps accumula- 25 tors, and pipe and valve systems such as usually employed where fluid under pressure is employed for opposing the movement of a yielding tool or forming part of a press.

The invention further provides a press of 30 the character mentioned above in which the amount or intensity of the reaction may be regulated.

An embodiment of the invention is illustrated in the accompanying drawing, in 35 which—

Figure 1 is a side elevation, partly in section, and

Fig. 2 is an enlarged sectional view of the 40 principal parts shown in Fig. 1, the line of section being at right angles to the plane of Fig. 1.

Referring to said drawings, numeral 10 designates the yielding forming part or tool, here embodied as the blank-holder of 45 a drawing press. 12 designates the punch or male forming part and 14 the die or female forming part. The punch 10 is mounted upon a part of the frame 15 of the press, here shown as the bolster plate 16, and the die 14 is mounted on the plunger 50 20, driven for example by a crank-shaft 22.

The punch 12 may serve to guide the yielding forming part or blank-holder 10, and it may be also guided and housed in a 55 box 24.

30 designates the vacuum means or device

for resisting the movement of said yielding part 10. This device 30 is conveniently in the form of a cylinder 32 having a plate or head 33 against which said yielding part 10 bears through pins 35, passing through holes in the bolster plate 16, or other suitable means of connection. A piston 37 is located inside of the cylinder 32, and connected to the bolster plate 16 of the frame 15 by means of a rod 39. The cylinder 32 is open to the atmosphere at the rear of the piston 37, through openings 41, so that any movement of the cylinder 32 is opposed by the pressure of the atmosphere on 60 the head 43 of said cylinder, the movement of said cylinder 32 producing a vacuum or partial vacuum therein between said piston 37 and the head 43.

The cylinder 32 and piston 37 are preferably so arranged that the head 43 is close to the piston, leaving substantially no space between said piston and cylinder head 43, so that there is initially substantially no air or gas within the cylinder to exert a counter-acting pressure to the pressure of the ambient air acting on the head 43 of the cylinder. A spring 45, or other suitable means, may be provided for pressing the head 43 of the cylinder toward the piston 37 and normally maintaining it in such position. The spring 45 is, however, preferably of such strength as not to appreciably modify the resistance offered by the pressure of the air to the movement of said cylinder 32. 75

Means may be provided for regulating the resistance offered by said vacuum means 30. These means may be in the form of a needle valve 50 controlling an opening 51 into the cylinder 32. Air admitted by the valve 50 may be ejected through said opening 51, or through a separate valve 57, on the return movement of said cylinder 32 and the yielding member 10 connected thereto. 80

Operation: The atmosphere or ambient air, at any given place, has a constant pressure per unit of area. Consequently, when the die 14 presses the margin of a blank X against the yielding blank-holder 10, the movement of said blank-holder 10 is resisted by the vacuum device 30, the amount of this resistance being represented by the product of the area of the head 43 of said piston and multiplied by the pressure per unit of area of the ambient air, around 15 pounds per square inch, and this pressure, moreover, will be constant throughout the 100 105 110

movement of the cylinder 32, and of the yielding part 10. If less than full atmospheric pressure is desired on the cylinder 32, the needle valve 50 may be opened 5 to admit air to exert a partial pressure tending to offset the full atmospheric pressure on the outside of the head 43.

On the return stroke of the plunger 20, the continued pressure of the ambient air 10 on the cylinder head 43, transmitted through the plate 33 and connections 35, causes the yielding part or blank-holder 10 to follow the die 14, any air contained in said cylinder 32 compressed to atmospheric pressure 15 being ejected through the opening 51, or through the valve 57 where such a valve is provided by the action of spring 45, thus returning the parts to initial position.

The idea of invention may receive other 20 embodiments than that therein specifically illustrated and described.

What I claim is:—

1. A drawing press of the type having 25 three forming parts, two of which are relatively oppositely movable male and female parts for producing a cup or shell from a blank, and the third adapted to make contact through said blank with one of said two oppositely movable parts and to yield 30 to the movement thereof, comprising a vacuum producing means connected to and adapted to resist the movement of said yielding part.

2. A drawing press of the type having 35 three forming parts, two of which are relatively oppositely movable male and female parts for producing a cup or shell from a blank, and the third adapted to make contact through said blank with one of said 40 two oppositely movable parts and to yield to the movement thereof, comprising a vacuum producing means connected to and adapted to resist the movement of said yielding part, and means for allowing air to enter said vacuum 45 producing means to regulate the resistance offered by said vacuum producing means.

3. A drawing press of the type having 50 three forming parts, two of which are relatively oppositely movable male and female parts for producing a cup or shell from a blank, and the third adapted to make contact through said blank with one of said two oppositely movable parts and to yield to the 55 movement thereof, comprising a vacuum producing means connected to and adapted to resist the movement of said yielding part, said vacuum producing means comprising a cylinder and piston one of which is connected to said yielding forming part.

4. A drawing press of the type having 60 three forming parts, two of which are relatively oppositely movable male and female parts for producing a cup or shell from a 65 blank, and the third adapted to make con-

tact through said blank with one of said two oppositely movable parts and to yield to the movement thereof, comprising a vacuum producing means connected to and adapted to resist the movement of said yielding part, 70 said vacuum producing means comprising a cylinder and piston, said piston being fixedly connected to said press, and said cylinder being connected to said yielding forming part.

5. A drawing press of the type having three forming parts, two of which are relatively oppositely movable male and female parts for producing a cup or shell from a blank, and the third adapted to make contact through said blank with one of said two oppositely movable parts and to yield to the movement thereof, comprising a vacuum producing means connected to and adapted to resist the movement of said yielding part, 75 said vacuum producing means comprising a cylinder and piston one of which is connected to said yielding forming part, and means for allowing air to enter said vacuum producing means to regulate the resistance offered by said vacuum producing means.

6. A drawing press of the type having three forming parts, two of which are relatively oppositely movable male and female parts for producing a cup or shell from a blank, and the third adapted to make contact through said blank with one of said two oppositely movable parts and to yield to the movement thereof, comprising a vacuum producing means connected to and adapted to resist the movement of said yielding part, 80 and means for returning said vacuum producing means to an initial position leaving substantially no space in said vacuum producing means for air.

7. A drawing press of the type having three forming parts, two of which are relatively oppositely movable male and female parts for producing a cup or shell from a blank, and the third adapted to make contact through said blank with one of said two oppositely movable parts and to yield to the movement thereof, comprising a vacuum producing means connected to and adapted to resist the movement of said yielding part, 85 said vacuum producing means comprising a cylinder and piston one of which is connected to said yielding forming part, and means for returning said cylinder and piston to an initial position leaving substantially no space therein for air.

8. A drawing press of the type having three forming parts, two of which are relatively oppositely movable male and female parts for producing a cup or shell from a blank, and the third adapted to make contact through said blank with one of said two oppositely movable parts and to yield to the movement thereof, comprising a vacuum producing means connected to and adapted 90

to resist the movement of said yielding part, said vacuum producing means comprising a cylinder and piston, said piston being fixedly connected to said press, and said cylinder 5 being connected to said yielding forming part, said piston being mounted on a rod suspended from the press and said cylinder having a head sliding on said rod.

9. A drawing press of the type having 10 three forming parts, two of which are relatively oppositely movable male and female parts for producing a cup or shell from a blank, and the third adapted to make contact through said blank with one of said 15 two oppositely movable parts and to yield

to the movement thereof, comprising a vacuum producing means connected to and adapted to resist the movement of said yielding part, said vacuum producing means comprising a cylinder and piston, said piston being fixedly connected to said press, and said cylinder being connected to said yielding forming part, said piston being mounted on a rod suspended from the press 20 and said cylinder having a head sliding on said rod, said connections to said yielding forming part being on said head.

In witness whereof, I have hereunto signed my name.

WILLIAM KLOCKE.
